WILLIAM S. PARKER AND JOSEPH JESPERSON, OF ROCKFORD, ILLINOIS, ASSIGNEES
TO BURSON KNITTING COMPANY, OF ROCKFORD, ILLINOIS, A CORPORATION OF
ILLINOIS.

FASHIONING INDICES AND METHOD OF KNITTING THE SAME.

Application filed June 17, 1921. Serial No. 478,842.

To all whom it may concern:

Be it known that WILLIAM S. PARKER and JOSEPH JESPERSON, citizens of the United States, residing at Rockford, in the county of Winnebago and State of Illinois, have invented certain new and useful Improvements in Fashioning Indices and Methods of Knitting the Same, of which the following is a specification.

This invention relating in general to knitting, has more particular reference to the knitting of fashioned articles, especially ladies' stockings. In the class to which this invention has particular reference the stocking is knit to shape and is fashioned in the knitting by bringing additional needles into action according to the particular design, thereby producing a fashioned seamless stocking as distinguished from that class in which a flat fabric is knit to shape and the edges united in a seam extending the full length of the stocking. The "widening" at the back of a fashioned seamless stocking has somewhat the appearance of a knit seam, this effect being produced by bringing the additional needles into action as the fashioning or widening progresses. This effect is not very pronounced, and in fact, is often unnoticed by the purchasing public, so that in some instances purchasers assume or are led to believe that stockings knit in this manner are not fashioned.

One of the objects of our invention is to overcome this erroneous impression and to produce a novel fashioned seamless stocking by incorporating in the fabric what we have termed "fashioning indices." These fashioning indices are arranged in a series paralleling each side of the widening and produce in combination therewith a full-fashioned effect having a distinctly different appearance from, and more pronounced and desirable than, the usual widening or fashioning, without the objectionable heavy seam common to the flat knit fabric stocking mentioned above.

While our invention contemplates in its broadest sense the production of these fashioning indices in a fashioned seamless article in any suitable design or arrangement, or by any suitable knitting process, nevertheless, we have devised and our invention contemplates as an object, a preferred method of knitting said fashioning indices,

as will be explained more fully hereinafter. 55
Other objects and attendant advantages will be appreciated by those skilled in this art as the invention becomes better understood by reference to the following description when considered in connection with the 60 accompanying drawings, in which—

Figure 1 is a rear view of a fashioned seamless stocking embodying our invention, the fashioning indices being represented diagrammatically; and 65

Fig. 2, an enlarged detail of a preferred form of fashioning index.

In the present instance, we have taken as an example illustrating our invention, a fashioned seamless fabric in the form of a 70 lady's stocking. The seamless fabric 3 is knit on a straight-bed knitting machine and the fashioning is produced in the usual well known manner by the addition of needles at the widening, extending in the example 75 shown, between the points indicated by reference characters 4 and 5.

Our invention contemplates provision of a series or row of fashioning indices in 80 juxtaposition to each side of the widening, and preferably following the angle thereof and located at suitably spaced intervals to give the desired effect. Referring now more particularly to Fig. 2, showing in enlarged detail the knitted fabric constituting 85 a fashioning index, it will be observed that this is formed as follows: One of the needles in a given course is held back during the usual course of knitting, thereby holding the yarn or loop on the needle. This needle 90 is held during two or more courses of knitting, and then brought into action, so that a relatively long loop is produced. In the example shown, a group of adjoining courses are indicated by numerals 6 to 11 inclusive 95 in successive order of knitting, the fabric in this instance being knit to the left as indicated by the arrow. The knitting is regular up to the courses 6 and 7. At the next course 8 the needle knitting the loops 12 100 will be held back out of action so that the yarn will simply traverse the needle space for the loop 12, causing a slack of yarn 13 at this gap. The said needle will be held out during the knitting of courses 9 and 10, 105 producing additional slack yarns 14 and 15 in said gap. Upon the next course of knitting, the needle which was held out will be

100
105

returned to action and the loop 16 of course 7 will be taken up by the yarn 11, thereby resuming the regular knitting.

As a result of this novel method of knitting, the knitted fabric will be slightly drawn or puckered by reason of the relatively large gap that must be traversed by the loop 16 which is under the same tension as the regular loop. A desirable effect may 10 be produced by simply holding the needle out of action for two courses, although a more effective and symmetrical index is produced by holding the needle out for three courses. After knitting a fashioning index 15 in this manner, the knitting is continued in the regular manner and subsequently another needle which has been brought into the fashioning will be held out to produce another fashioning index. In the present 20 instance, every fourth needle substantially throughout the length of the widening will be held out at a given point with the result that a series of fashioning indices will be produced at each side of the widening as 25 indicated by the heavy dots 17 in Fig. 1. It will be further observed that each fashioning index is located a uniform distance from the line of widening (indicated by reference numerals 4-5) and composed of a 30 structural variation in a plurality of successive courses in a given wale separated by a plurality of intermediate wales of plain, regular knitting. These fashioning indices are so co-ordinated with the widening as to 35 accentuate the same and to plainly and distinctly set out the fashioning or widening

effect without the objectionable heavy seam common to other forms of knitting.

It is believed that the foregoing conveys a clear understanding of the objects 40 prefaced above, and while we have illustrated but a single working embodiment of our invention, it should be understood that considerable change might be made in the detail and the form and arrangement of the 45 fashioning indices without departing from the spirit and scope of the invention as expressed in the appended claims, in which—

We claim:

1. A seamless stocking fashioned by 50 widening, having fashioning indices at each side of the line of widening, each fashioning index being located a uniform distance from said line of widening and composed of a 55 structural variation in a plurality of successive courses in a given wale separated by a plurality of intermediate wales of plain, regular knitting.

2. The method of knitting fashioning indices in a seamless stocking fashioned by 60 widening, consisting in holding out of action for one or more successive courses during the knitting of the widened portion, one needle at each side of and a uniform distance from the line of widening and separated by a plurality of intermediate wales 65 of plain, regular knitting, whereby to produce a row of finishing indices paralleling each side of the line of widening.

WILLIAM S. PARKER,
JOSEPH JESPERSON.
